MARCELLUS A. MORSE, OF TITUSVILLE, PENNSYLVANIA.

Letters Patent No. 101,493, dated April 5, 1870.

IMPROVEMENT IN WALKING-BEAM AND SUCKER-ROD CONNECTIONS FOR DEEP WELLS.

The Schedule referred to in these Letters Patent and making part of the same.

To all whom it may concern:

Be it known that I, MARCELLUS A. MORSE, of the city of Titusville, in the county of Crawford and State of Pennsylvania, have invented a new and useful improved Connection of Sucker-rods and Walking-beam for Operating Deep Wells; and I do hereby declare the following to be a full, clear, and exact description thereof, reference being had to the accompanying drawing making a part of this specification, in which—

Figure 1 is a front or end view of my improvement;

Figure 2 is a side elevation thereof;

Figure 3 is a sectional view of the connecting-joint;

Figure 4 is a perspective view of the gib or pressure-block; and

Figure 5 is a perspective view of the set-screw.

Like letters of reference indicate like parts in each.

My invention, while useful in operating deep wells generally, is of especial value in the pumping of oil-wells, since, to secure the greatest possible yield of oil, it is necessary that the piston be carefully adjusted in the working-barrel, at the required depth in the well, with especial reference to the location of the sand or oil-producing rock.

The sucker-rods extend from the piston up to the mouth of the well, and by a rod, which is jointed to a stirrup on the end of the walking-beam, are connected with the latter.

Such connection, hitherto in general use, provides no means by which the piston can be sufficiently adjusted, so as to operate at a point higher or lower.

My invention relates to an improved joint for effecting such an adjustment; and

The nature of it consists in combining a solid mortised head-piece, having cylindrical trunnions, with a concave-ended set-screw, for holding an adjustable connecting-rod, which passes through the mortise in the head-piece, at any desired point of adjustment.

Also, in combining a gib or pressure-block with an adjustable connecting-rod, mortised head-piece, and set-screw.

To enable others skilled in the art to make and use my invention, I will proceed to describe its construction and mode of operation.

The walking-beam A is slotted at its forward end, and on the upper face of each of the bifurcations A', a concave seat is made for the cylindrical trunnions a' of the head-piece a.

This latter is a solid block of metal, except that it has a mortise, c, extending through it, through which passes the connecting-rod b, the lower end of which is to be jointed to the sucker-rods.

Also, a tapped hole is made in one side of the

head-piece a at, or nearly at, right angles to the direction of the mortise c, in which a set-screw, d, operates, the parts being so arranged that the inner end of the set-screw d shall bear against the connecting-rod b, or against a gib or pressure-block, e, inserted in the mortise c between the two.

This pressure-block may be of any desired length, its inner face plane or corrugated, as also the face of the mortise c opposite thereto, if so desired, the object being, by turning the screw d tightly up against the block e, to produce so firm a bite on the rod b that it cannot slip, even under the immense load that has to be raised with each upward stroke of the walking-beam.

The block e may, however, be dispensed with, and a sufficiently secure bite be obtained by making the inner end of the screw d concave or cup-shaped, as as d'.

Then, when it is screwed well up against the rod b, the edges of the concave end will take so secure a bite on the rod b that it will be held at any desired point of adjustment.

The concave-ended set-screw may, however, if so desired, be advantageously used with the pressure-block e.

With the devices described, it is but a moment's work to raise or lower the rod b in the mortise c, nothing being necessary thereto except to loosen and tighten the screw d, which can be done with a wrench.

For convenience in holding the block e in place while the adjustment of the rod b is being effected, its rear face may be notched or rabbeted, as shown.

As an improved mode of attaching the head-piece a to the walking-beam, I hinge to it a cap, f, also slotted at its forward end, and on the under side of each bifurcation f' make a concave seat, g, so that when the cap is closed down, as in fig. 2, the trunnions a' will play therein, as well as in the seat g' on the walking-beam.

A bolt h is fixed in the body of the beam, having a screw-thread on its upper end.

A hole is made in the cap, through which the bolt h projects when the cap is down.

To hold the cap down, and so keep the head-piece a in place, I place a cross-bar, i, which is perforated at about its middle point, for the purpose, and turn down onto it a threaded nut, i', being careful, however, not to screw it down so tightly as to make the friction on the trunnions a' too great.

The devices described are then easily taken out for repairs, or for other purposes, and as easily replaced, and while in place are securely held.

They are simple in construction, cheap, and durable.

What I claim as my invention, and desire to secure by Letters Patent, is—

1. The solid head-piece *a*, having trunnions *a'* and mortise *c*, in combination with a concave-ended set-screw, *d*, and slotted walking-beam *A*, constructed and arranged substantially in the manner and for the purpose set forth.

2. In a walking-beam and sucker-rod connection, the pressure-block *e* with plane or corrugated face, in

combination with an adjustable connecting-rod, mortised head-piece, and set-screw, constructed and arranged substantially as and for the purposes described.

In testimony whereof I, the said MARCELLUS A. MORSE, have hereunto set my hand.

MARCELLUS A. MORSE.
